UNITED STATES PATENT OFFICE.

IRVING A. TAYLOR, OF WORCESTER, MASSACHUSETTS, ASSIGNOR TO S. RILEY STOKER CORPORATION, OF WORCESTER, MASSACHUSETTS, A CORPORATION OF MASSACHUSETTS.

FURNACE-WALL AIR PLATE.

Application filed November 6, 1923. Serial No. 673,162.

This invention relates to furnaces having an automatic feed by which the fuel is moved rearward or laterally during combustion, so that the ash and refuse accumulates against a rear or side wall of the furnace. This ash and refuse usually contains a certain amount of combustible material which should be fully consumed to maintain the efficiency of the furnace.

10 It is the general object of my invention to provide an improved construction by which air may be admitted to the ash and refuse adjacent the furnace wall, so that the combustible material may be fully consumed.

15 Another object is to provide a construction by which the air thus admitted will act to cool the wall structure and prevent burning thereof.

20 My invention further consists in the provision in a furnace wall of a plurality of air admitting blocks or plates so constructed that they may be separately placed in position or removed therefrom with a minimum expenditure of time and labor.

25 My invention further relates to an improved arrangement for supplying air to such plates by both forced and natural draft so that the plates may be kept cool under all operating conditions.

30 I have shown my invention as embodied in a furnace in which the coal is moved rearward toward the bridge wall, at which point the ash and refuse is supported upon dumping plates of the type shown in the prior patent to Riley No. 1,322,822, issued Nov. 25, 1919.

35 My invention further relates to arrangements and combinations of parts which will be hereinafter described and more particularly pointed out in the appended claims.

40 A preferred form of the invention is shown in the drawings in which—

Fig. 1 is a front elevation of several of my improved furnace wall air plates in position in the bridge wall of a furnace;

45 Fig. 2 is a sectional plan view taken along the line 2—2 in Fig. 1, with certain of the plates shown in full plan view;

Fig. 3 is a reduced sectional elevation, 50 taken along the line 3—3 in Fig. 1 and showing also the relative position of the ash supporting dump plates, and

Fig. 4 is a perspective view of one of the air admitting plates.

55 Referring particularly to Fig. 3, I have

indicated a furnace rear or bridge wall 10, a portion of a side wall 11, and dumping plates 12 of the general type disclosed in the prior patent to Riley above identified. These plates 12 are connected for oscillating motion with the side walls of the stoker retorts and are supported upon rolls 13 carried by rack bars 14 which may be withdrawn or moved forward to permit dumping of the ash and refuse supported on the plates 12. For a detailed description of the construction of these dumping plates, together with the other usual parts of the underfeed furnace to which they pertain, reference is again made to the patent to Riley No. 1,322,822.

The wall 10 is formed with a recessed portion 15 in which a channel iron or beam casting 16 extends across the rear of the furnace. This channel iron or beam 16 is 75 built into the wall 10 and forms a permanent part of the structure thereof. The beam 16 is provided with an upwardly extending rib or flange 17 and a corresponding depending rib or flange 18, the ribs 17 and 18 extending from end to end of the beam 16.

Air plates 20 are provided, having upper and lower grooves or recesses 21 and 22 adapted to receive the flanges 17 and 18. The groove 21 is deep enough so that the 85 block may be pushed upward to pass over the rib 17, after which the block is dropped into place and the ribs 17 and 18 prevent accidental movement thereof.

When it is desired to remove a plate 20, 90 it is merely necessary to raise the plate and swing the lower end outward or forward, thus reversing the operation of inserting the plate. Each plate 20 is provided with a forwardly extending flange 23 and with air 95 passages 24 formed in the side thereof. The flanges 23 form vertically extended air discharge openings between the plates and engage and laterally support the refuse.

An angle iron 25 may be secured to the 100 beam 16 by bolts 26 and engages the back side of the plates 20, thus supporting the plates and preventing rearward movement thereof. This angle iron divides the space behind the plates 20 into upper and lower 105 air passages 27 and 28. When thus divided, it is desirable to connect the lower air passage 28 by a pipe 30 (Fig. 1) to a blower (not shown) or other convenient supply of air under pressure, so that air may be forced 110

outward through the air passages 24 between the plates 20 to complete the combustion in the ash and refuse on the dumping plates 12.

The upper air passage 27 may be open to atmosphere in the boiler room at one end, as indicated in dotted lines at 31 in Fig. 1, and may be connected by a pipe 32 at the opposite end to the furnace stack (not shown). A current of air will thus be drawn through the air passage 27 to cool the wall plates 20 at all times, whether or not forced air is being supplied to the lower air passage 28.

The flow of air through either passage 27 or 28 may be under natural draft or under pressure to suit operating conditions.

As the dump plates 12 are oscillated in accordance with the disclosure in the Riley patent above cited, the ash and clinkers supported thereby are crushed between the dump plates 12 and the wall plates 20. The wall plates provide a very rigid and durable structure to crush the refuse.

Having thus described my invention and the advantages thereof, I do not wish to be limited to the details herein disclosed otherwise than as set forth in the claims, but what I claim is:—

1. In a furnace, in combination, a furnace wall having a recess, an ash support adjacent thereto, members forming upper and lower ribs in said recess, and a plurality of air-admitting plates mounted at the front of said recess and having end grooves to receive said ribs, the upper grooves being deep enough to permit lifting said plates to clear the lower ribs for removal from said furnace.

2. In a furnace, in combination, a furnace wall having a recess, members forming upper and lower ribs in said recess, an ash support adjacent said recess, a plurality of air-admitting plates removably mounted in said recess and having end grooves to receive said ribs, and means to supply air under pressure through said plates to the refuse on said ash support, said plates each having a relatively thin vertically extending flange projecting forward from the main portion of said plate and laterally supporting the fuel and spaced apart throughout their length when assembled, thus providing vertical air discharge openings between adjacent plates.

3. In a furnace, in combination, a furnace wall having a recess, an ash support adjacent thereto, a plurality of air-admitting plates removably mounted in said recess and spaced from the rear wall of said recess to form an enclosed air space therewith, said plates having air openings therethrough from a portion of said enclosed air space, and a member dividing said enclosed air space into

upper and lower air passages, one of said passages receiving air under pressure and 65 delivering the same through said air openings to support combustion on said ash support, and the other passage receiving air to cool said plates.

4. A protective bridge wall plate comprising a bar having hooks on its upper and lower rear portions arranged to be removably hooked over supports on the bridge wall, and a lateral flange arranged to co-operate with like parts on other bars to 75 form a substantially continuous surface with air openings therethrough, and said plate forming a member against which clinkers may be crushed.

5. A bridge wall plate for forming a protective portion of a furnace bridge wall comprising a long, narrow and deep bar having front and rear flanges arranged to co-operate with like parts of other plates to form two substantially continuous spaced walls having 85 an air passage therebetween, an opening through the rear flange to the air passage and a tuyère opening through the front flange to feed air to the fire, the flow of air being substantially limited by the size of the 90 opening in the rear flange, whereby if the front flange portions of a series of bars are burned through, the amount of air admitted to the fire is not materially increased.

6. A bridge wall plate comprising a bar 95 having its ends shaped to form supporting hooks and having two lateral flanges, one flange forming the rear face and having an air opening therethrough, and the other flange having a tuyère opening out of alignment with said air opening, the space between the flanges forming an air passage connecting the air opening and the tuyère opening when the plate is assembled with like plates to form a wall.

7. A furnace comprising a bridge wall, a stoker having a dump plate separated from the bridge wall to form an ash pit, and to support ashes in the bottom of the pit, said parts being so arranged that ashes may contact with the bridge wall opposite the dump plate, a series of wall plates each separately removably mounted on the bridge wall, opposed to the dump plate and constructed to withstand the crushing of clinkers thereagainst, each wall plate having top and bottom hooks on its rear portion and a tuyère opening in front, co-operating parts on the wall to hold the plate removably in position, and means forming an air passage 110 in the rear of the wall plates for circulating air in the rear of the plates and through said tuyère openings.

In testimony whereof I have hereunto affixed my signature.

IRVING A. TAYLOR.
